UNITED STATES PATENT OFFICE.

HERBERT L. MOSHER, OF DOWAGIAC, MICHIGAN.

DESIGN FOR A HEATING-STOVE.

SPECIFICATION forming part of Design No. 26,655, dated February 16, 1897.

Application filed October 7, 1895. Serial No. 564,972. Term of patent 14 years.

To all whom it may concern:

Be it known that I, HERBERT L. MOSHER, a citizen of the United States, residing at the village of Dowagiac, in the county of Cass and State of Michigan, have invented a certain new and useful Design for a Heating-Stove, of which the following is a specification.

My invention relates to a design for a heating-stove.

It relates more especially to the design of the legs and ornamentation extending therefrom up the sides of the stove and the ornamental bracket or urn-holder on the top of the same. These features of the design can be used when the remaining parts of the stove are decorated in any manner desired and are considered to be the essential features of the design.

My invention relates particularly to the stove illustrated complete in the accompanying drawing, which presents a perspective view of the stove constructed in accordance with my design.

The leading feature of my design consists of an upright stove-body of any ordinary outline. The body is supported by the ornamental legs B, which are formed into spirals at the bottom and extend along the sides of the stove in a light scrollwork. As shown

in the drawing, the lower part serves as the 30 legs for the stove and the upper portion for the ornamentation purely. On the stove-top is an ornament or urn-holder D, constructed of light iron scrollwork which is adapted to carry, in this instance, a small teakettle or 35 other article of that description or any suitable receptacle which it may be desired to place there.

It is not material to my design as here shown what ornamentation or configuration is given 40 to the main body of the stove, the principal features of the design being the ornamental legs and scrollwork at the sides of the stove and the ornamental bracket or urn-support 45 at the top of the same, these being the principal features of the design and the other parts being only incidental, but not essential parts of the design.

Having thus described my design, what I claim is—

The design for a heating-stove, as herein 50 described and shown.

In witness whereof I have hereunto set my hand and seal in the presence of two witnesses.

HERBERT L. MOSHER. [L. S.]
